Primary Examiner — Calvin E Vansant*Assistant Examiner* — Kaitlyn G Wiltshire(74) *Attorney, Agent, or Firm* — Hanrahan Law Firm, P.A.; Benjamin M. Hanrahan(57) **CLAIM**

The ornamental design for a bearing housing as shown and described.

DESCRIPTION

FIG. 1 is a front-bottom perspective view illustrating our design for a bearing housing.

FIG. 2 is a bottom view thereof.

FIG. 3 is a top view thereof.

FIG. 4 is a front view thereof.

FIG. 5 is a rear view thereof.

FIG. 6 is a right-side view thereof; and,

FIG. 7 is a left-side view thereof.

The broken lines show portions of the article form no part of the claimed design.

1 Claim, 7 Drawing Sheets(56)
